INVENTOR,

William G. Walter.

UNITED STATES PATENT OFFICE.

WILLIAM G. WALTER, OF PITTSBURG, PENNSYLVANIA.

DESIGN FOR A BOTTLE.

SPECIFICATION forming part of Design No. 19,357, dated October 15, 1889.

Application filed August 17, 1889. Serial No. 321,161. Term of patent 3½ years.

To all whom it may concern:

Be it known that I, WILLIAM G. WALTER, of Pittsburgh, in the county of Allegheny and State of Pennsylvania, have invented a new and useful Design for Bottles, of which the following is a full, clear, and exact description, reference being had to the accompanying drawing, forming part of this specification, which shows a side elevation of a glass bottle embodying my design.

The design consists in a bottle whose exterior shape or configuration is that of a dagger having a sheath and a projecting handle portion, and in certain features of surface ornamentation hereinafter described and claimed.

Referring to the drawing, *a* represents the lower part of the bottle, whose form is that of a dagger-sheath, the lower end being somewhat tapered or pointed and the upper por-

tion being ornamented by a scroll *b*. Between the scroll and the base of the sheath is a triangular figure the outlines of which are filled in with corrugations.

c is the projecting handle portion forming the neck of the bottle. It is ornamented by an external spiral figure.

I claim—

The design for bottles, consisting in a bottle formed with a body portion *a*, whose external form is that of a sheathed dagger, an elongated and contracted neck, and an intermediate scroll, substantially as shown and described.

In testimony whereof I have hereunto set my hand this 3d day of August, A. D. 1889.

WILLIAM G. WALTER.
